BOTTLE CARRIER

Frank A. Wyatt, Indiana, Pa.

Application December 17, 1948, Serial No. 65,875

6 Claims. (Cl. 224—48)

1

This invention relates to devices for carrying bottles and has for its object the provision of a collapsible carrier which will firmly hold a number of bottles in such a manner as to protect the trade mark or advertising on the surfaces thereof from impairment or obliteration.

Another object of my present invention is to provide a light weight and compact bottle carrier the lateral compartments of which may be individually collapsed toward the center when emptied in order to afford greater carrying convenience and to require less storage space on a delivery truck, in the retail store and in the home.

Still another advantage of my carrier is the presence of a carrying handle which may be turned to a position within its upper margin allowing another carrier to be placed thereon to facilitate storage and shipping of the carriers in either a loaded or collapsed condition.

Still other objects and advantages will become apparent from the following description of the present invention illustrated in the accompanying drawing in which:

Figure 1 is a perspective view of a bottle carrier embodying my invention shown completely collapsed.

Figure 2 is a perspective view of the carrier fully opened to receive a maximum number of bottles.

Figure 3 is a sectional view taken on line 3—3 of Fig. 2.

Fig. 4 is a sectional view taken on line 4—4 of Fig. 2.

Fig. 5 is a sectional view taken on line 5—5 of Fig. 2.

Similar reference characters in the several figures represent similar parts.

One of the primary difficulties confronted in the continuous handling of glass-bottled products by the shipper, dealer and consumer is the costly impairment or damage done to descriptive material appearing on the cylindrical surface of the bottle and also the marring of the surface of the glass itself where one bottle is allowed to rub against another. This descriptive material, which customarily consists of lettering or trademarks raised on the surface of the bottle or merely painted thereon, is seriously abraded by constant contact of each bottle with the sides of the carrier or crate or with other bottles therein. Since certain industries, such as those manufacturing and selling soft drinks and the like, have found it most economical to reuse bottles as many times as they can be reclaimed,

2

it will be readily understood that a portion of the effectiveness of this economic endeavor is defeated by the necessity of discarding or reprocessing bottles upon which the descriptive material has been damaged. Obviously, to present a product to the consuming public in bottles which are chipped or otherwise unsightly detracts from its saleability since the purchaser instinctively shuns an object with an unpleasant or ill-kept appearance.

With the above in mind, I have devised the bottle carrier shown in Figs. 1 and 2 which will hold bottles firmly for protecting the raised lettering or trade-mark and which is constructed in such a manner as to facilitate storage and shipping.

The foundation of my bottle carrier, as seen in Fig. 2, consists of a pair of vertical support members 10—10^a. These members have attached thereto left and right hand lateral carrying compartments 11—11^a each comprising a side panel 12 and a bottom panel 13. The ends of each bottom panel 13 are formed with flanges 14 vertically projecting at right angles to the surface of the panel. The inner ends of these flanges are pivotally connected respectively to the vertical supports 10—10^a (Figs. 2 and 5) by means of small bolts or rivets 16 which pass through aligned apertures located at the inner end of the flange and the lower corner of the vertical support member.

The outer end of each flange 14 projects beyond the edge of the bottom panel and has pivotally connected thereto the projecting extremity 17 of a flange 18 formed at each end of the side panel 12. A similar rivet 19 is preferred for this connection.

The upper end of each flange 18 is respectively joined to its proximate vertical support 10—10^a by a connecting bar 20, the latter being pivotally connected at one end to the flange 18 by a rivet 21 and at its other end to the vertical member by a small bolt 22 and retaining nut 23 as shown in Figs. 2 and 4.

As will be seen in Fig. 2, the vertical support members 10—10^a are reinforced by the narrow projections 24 which are bent inwardly to lie against the inner face of the members and each member is further provided at the upper portion thereof with a pair of longitudinal slots 25 and 25^a. These slots are parallel and are each of a width slightly greater than the diameter of the connecting bolts 22 to permit vertical sliding of the latter when the carrier is collapsed or opened, as the case may be.

The upper edge of each side panel 12 is formed with a bottle holding flange 26 bent inwardly from the plane of the side panel at an inclination of about 45° therefrom. The length of flange 26 is of necessity less than the distance between the vertical support members 10—10^a to permit the flange to pass between these members when the carrier is collapsed as shown in Fig. 1. Successive arcuate recessions 27 for laterally supporting bottles are formed in the free edge of flange 26 and are spaced by lobes 28 which are accordingly designed with a sufficient thickness to prevent contact between the cylindrical surfaces of adjacent bottles in the carrier. A pair of terminal lobes define the ends of the series of arcuate recessions and prevent contact between the surface of the end bottles and the adjacent elements forming the ends of the bottle carrier.

Cooperating with the flange recessions 27, to firmly hold the bottles in their segregated relationship is a series of similar arcuate recessions 30 formed in each of the oppositely disposed wings 31 of a central retainer 32. As seen in Fig. 4 the retainer comprises a longitudinal rod 33 journaled at either end within apertures located on the center line of vertical support members 10—10^a. The ends of the rods are enlarged to provide retaining heads 34. The retainer 32 compressing a thin strip of metal has its central portion bent around rod 33 to substantially envelope the same, as shown at 35 in Fig. 4 and laterally projecting therefrom are its edges which form the bottle supporting wings 31 previously mentioned.

As will be seen in Fig. 2 the arcuate recessions 27 and 30 in each lateral compartment of my bottle carrier are aligned in pairs to firmly hold the bottles in place with a minimum of contact between the carrier and each bottle. Furthermore, the arcuate line of contact as shown in the drawings will normally lie above the area of any descriptive material carried by the bottle. I prefer to round the lobes separating each arcuate recess to prevent the presence of unnecessary pointed projections which might injure the hands or clothing of a user.

Since conservation of shipping and storage space is an important factor in the industry, I have provided a carrying handle which may be rotated to the inoperative position shown in Fig. 1 and thereby permit either loaded or collapsed carriers to be stacked on top of each other. The handle 36 is rigidly secured to a longitudinal carrying rod 37 by means of a pair of screws 38. The screws pass through the flanges 39 at the ends of the handle and are received in aligned threaded holes in the rod. In order to make the carrying assembly rotatable about the axis of the rod 37, I provide each end of the rod with a shallow axial bore threaded to receive a screw 40 which passes through an aperture 41 at the upper end of the vertical supporting members.

The unique association of the pivoted elements embodied in my present invention adds to the effectiveness of the carrier in that when it does not contain bottles the connecting bars 20 may be caused to slide upwardly in their respective guide slots 25—25^a allowing each lateral compartment 11—11^a to be inwardly collapsed to a position shown in Fig. 1. The compact package thus formed is of a thickness approximately equal to the vertical supporting members 10—10^a since each side panel 12 is swung upwardly and inwardly permitting the bottom panels 13 to pivot on the rivets 16 to a vertical position as shown,

To further compact the collapsed assembly, the handle and rod 37 may then be rotated until the handle extends downwardly and will thus rest entirely within the outline of the package.

It will be seen from Fig. 2 that should the number of bottles contained by the carrier illustrated be less than four the empty compartment can be individually collapsed to provide a more easily carried article or to occupy a minimum of space in a kitchen or pantry.

It will of course be understood that the size of the various elements of the carrier will be dependent upon the size of the bottles with which the carrier is to be used. Furthermore, while I have shown a carrier with a capacity of six bottles, the compartments may be made to accommodate any desired number of bottles by increasing the number of arcuate recessions accordingly.

While a preferred form of the invention has been shown and described, variation in details of form may be made without departure from the invention as defined in the appended claims.

I claim:

1. In a bottle carrier, the combination of vertical end members each having parallel guide slots formed therein, lateral compartments pivotally connected to said end members and having hinged side and bottom panels thereon, slidable bars connecting said side panels to said slotted end members, an inclined flange at the upper end of each of said side panels having successive arcuate recessions spaced in the edge thereof, a longitudinal rod journally supported by said end members, a retaining member enveloping said rod and having lateral wings thereon, said wings being formed with successive arcuate recessions aligned with said flange recession for holding bottles.

2. In combination with a bottle carrier having vertical end members and individually collapsible lateral compartments comprising side and bottom panel sections, an inclined flange at the upper end of each of said side panels having successive arcuate recessions spaced in the edge thereof, a longitudinal rod journally supported by said end members, a retaining member enveloping said rod and having lateral wings thereon, said wings being formed with successive arcuate recessions aligned with said flange recession for holding bottles.

3. A collapsible bottle carrier comprising narrow vertical end members having parallel slots in the upper portion thereof, lateral bottom sections pivotally connected to the lower ends of said vertical members, side panels hinged to the outer extremities of said sections, connecting bars each having one end pivotally secured to an upper corner of a side panel and the other end to a vertical end member through one of said slots, a longitudinal rod rotatably supported by the upper ends of said vertical members having a carrying handle secured thereto, a central retaining member between the end members, said retaining member and side panels containing aligned arcuate recessions for holding bottles.

4. In a bottle carrier, the combination of vertical end members each having parallel guide slots formed therein, lateral compartments pivotally connected to said end members and having hinged side and bottom panels thereon, slidable bars connecting said side panels to said slotted end members, the side and bottom panels of each compartment being pivotally connected whereby the compartments may be collapsed into the

plane of said end members, a carrying handle rotatably supported by the upper ends of the end members, a central retaining member connecting said end members and means associated with said compartments and retaining member cooperating to hold the cylindrical surface of individual bottles from contact with other bottles and with elements of the carrier.

5. In a bottle carrier, the combination of vertical end members each having parallel guide slots formed therein, lateral compartments pivotally connected to said end members and having hinged side and bottom panels thereon, slidable bars connecting said side panels to said slotted end members, the side and bottom panels of each compartment being pivotally connected whereby the compartments may be collapsed into the plane of said end members, an inclined flange at the upper end of each of said side panels having successive arcuate recessions spaced in the edge thereof, a longitudinal rod journally supported by said end members, a retaining member enveloping said rod and having lateral wings thereon, said wings being formed with successive arcuate recessions alined with said flange recession for holding bottles.

6. A collapsible bottle carrier comprising narrow vertical end members having parallel slots in

the upper portion thereof, lateral bottom sections pivotally connected to the lower ends of said vertical members, side panels hinged to the outer extremities of said sections, connecting bars each having one end pivotally secured to an upper corner of a side panel and the other end to a vertical end member through one of said slots, the side and bottom panels of each compartment being pivotally connected whereby the compartments may be collapsed into the plane of said end members, a longitudinal rod rotatably supported by the upper ends of said vertical members having a carrying handle secured thereto, a central retaining member between the end members, said retaining member and side panels containing alined arcuate recessions for holding bottles.
